UNITED STATES PATENT OFFICE.

LUCY R. HENDERSON, OF PHOEBUS, VIRGINIA.

FIRE-ESCAPE.

1,292,772.

Specification of Letters Patent.

Patented Jan. 28, 1919.

Application filed February 12, 1917. Serial No. 148,198.

To all whom it may concern:

Be it known that I, LUCY R. HENDERSON, a citizen of the United States, residing at Phoebus, in the county of Elizabeth City, State of Virginia, have invented certain new and useful Improvements in Fire-Escapes; and I do hereby declare the following to be a full, clear, and exact description of the invention, such as will enable others skilled in the art to which it appertains to make and use the same.

This invention relates to improvements in fire-escapes.

One object of the present invention is to provide a novel and efficient device which is adapted for attachment to a window ledge for the purpose of securing one end of a rope which is to be lowered out of the window.

Another object is to provide an improved construction of device of this character which can be readily adjusted to apply to window ledges of different heights from the floor.

Another object of the present invention is to provide a device for attachment of a life saving rope line on a burning building which will hold the end of the rope from chafing or cutting.

Another object of the present invention is to provide a device which is adapted to be attached to the face of a building to provide a ladder to permit persons to escape from the building in case of fire.

A further object of the present invention is to provide a device of this character which is adapted to be attached to the window ledges, and to extend from one window to the next above or below, a number of the sections being used so as to produce a continuous ladder, the rope being held while descending the ladder.

Other objects and advantages will be apparent from the following description when taken in connection with the accompanying drawings.

In the drawing:

Figure 1 is a front elevation of the rope holding device attached to a window ledge and floor, and a rope attached to the same. Fig. 2 is a side elevation of the rope holding device, and the ladder, the window ledge and floor, as well as a portion of the wall being shown in section.

Fig. 3 is a vertical sectional view through the rope holding device removed from the window.

Fig. 4 is a front elevation of a portion of a building showing the arrangement of the ladder sections.

In the accompanying drawing, which 60 illustrates the preferred form of my invention, 10 represents a portion of a window ledge, and 11 a portion of the floor of a building with which my improved fire escape is particularly adapted for use. 65

The device consists of a lower vertical hollow standard 12, the lower end of which is formed with a horizontally extending foot or pedestal 13, formed with openings 14 for the reception of screws 15 by means of 70 which the same is attached to the floor beneath the window ledge. Extending laterally from opposite sides of the upper end of the standard are loops 16, the purpose of 75 which will be later set forth.

A second member 17 is formed with an angularly extending upper end 18 formed with openings 19 for the reception of screws 20 whereby the same is adapted for attachment to the window ledge. The lower portion of the member 17 is disposed for 80 slideable adjustment in the hollow standard 12, the attachment of the members to the ledge and floor holding the parts in proper adjusted positions. 85

In using the device, one end of a rope is passed through one of the loops 16, around the hollow standard and then through the other loop, where said rope is properly tied. The other end of the rope is then dropped 90 out of the window so that the person can descend thereon from the burning building.

It is the intention to attach one of these devices to each window of a building so that it will, at all times, be within convenient reach in case of fire, it being, of course, understood that a rope is provided in the room for this emergency. The device is especially adapted for use in hotels, office buildings, apartment houses, or like buildings where large numbers of people are employed or reside. 95

The ladder includes a body portion formed of metal of suitable thickness and of a length to reach from the window ledge 105 of one window to the top of the window of the story below, this body portion being represented by the reference character 21. On each side of the longer edges of the body of the strip are formed upwardly and outwardly inclined lugs 22, which form the steps or rungs of the ladder, the lugs on 110

one side being arranged in staggered relation to those of the other side. The upper end of the strip is bent at right angles to lie across the window sill and ledge, as shown at 23, the extremity of the said end being bent downwardly, as at 24, and secured to the inner portion of the window ledge, or stool of the window. The lower end of the strip is similarly formed with a Z-shaped portion 25, the foot of which is secured to the face of the building below the window sill, and above the window of the story below. An L-shaped portion 27 is carried by the upper portion of the strip for attachment to the building directly below the window ledge.

By providing a number of these sections, extending from window to window, and between the stories, there can thus be produced a continuous ladder from the top story or from the roof of the building, to the ground, by means of which the persons can readily

descend in case of fire, it being understood that the rope is held in the hands while descending the ladder to balance the persons. 25

What is claimed is:

A fire escape comprising a vertical hollow standard having a horizontal foot for attachment to a floor beneath the window of a building, a depending stem having its upper end formed with a transverse T-head for attachment to the window ledge and its other end slidably disposed in the hollow standard, and laterally extending loops on opposite sides of the upper end of the standard for passage therethrough and around the standard of one end of a life saving rope. 30

In testimony whereof, I affix my signature, in the presence of two witnesses.

LUCY R. HENDERSON.
